UNITED STATES PATENT OFFICE.

CHARLES K. CORDREY, OF BELLEFONTAINE, OHIO.

GATE FOR SWINGING BRIDGES.

SPECIFICATION forming part of Letters Patent No. 373,130, dated November 15, 1887.

Application filed August 19, 1886. Serial No. 211,356. (No model.)

To all whom it may concern:

Be it known that I, CHARLES K. CORDREY, a citizen of the United States, and a resident of Bellefontaine, in the county of Logan and 5 State of Ohio, have invented a new and useful Gate for Swinging Bridges, of which the following is a specification.

My device is an improvement in gates for use in connection with swinging bridges, and 10 is designed to close the entrance to a bridge as soon as or before the bridge begins to swing.

Figure 1 is a view of my gate open with the bridge ready to be swung open. Fig. 2 is a plan view of the devices underneath the bridge, 15 the floor of the bridge being removed to show the parts. Fig. 3 is a detail view of my trip, rock-shaft, oscillating post, and gate, showing the gate in upright position, and also, in dotted lines, in position across the street.

20 A represents my gate, pivoted at B to the side of the oscillating support C. D is a weight attached to rear end by chain or wire E. F is a swinging support for front end of gate when down; G, rock-shaft; H, journals for rock-shaft; I, crank-arm on end of rock-shaft; 25 K L, diverging lugs on arm I; Q, lantern on gate A, which by its position serves as a signal at night to show whether gate is open or closed; R, trip or rod on swinging bridge, that 30 strikes the lugs K L as the bridge swings around; S, stationary piece under floor of bridge, to which the trip R is pivoted at T; U, chain attached to trip R and passing around pulleys V, and attached to a hand wheel or 35 lever, W. Y represents the perpendicular face of the wall at the side of the stream.

The operation of my device is substantially as follows: At all swinging bridges in cities, over streams and other places, there is more or 40 less danger, when the bridge is swung around, of people rushing or falling off the pier in the opening made and into the water below, and especially are these places dangerous in the dark, and persons are often drowned by walking into these traps, and even teams are driven 45 into them. To obviate this danger I mount on the dock or pier a gate, A, on an oscillating upright post, C, and pivot it in a bracket on one side of the post. This bracket is so constructed that when the oscillating post C is in

an upright position the weighted end of the gate A rests against the post and prevents the gate going beyond a perpendicular; but when the post is leaning forward, as shown in dotted lines, Fig. 3, the gate is allowed to assume a 55 horizontal position and rest upon the top of the post. While the top of the post is in an inclined position (shown in Fig. 3) the pivot of the gate is above the level of the top of the post; but as the post is raised to a perpendicular, the gate being pivoted in a bracket on the rear of the post and below the top, the top of the post rises higher than the pivot, causing the gate to assume an approximately 60 vertical position again, while the momentum 65 of the gate carries it past the perpendicular until its bottom end rests against the post. The post C is attached at its lower end to the rock-shaft G, which has an arm, I, with lugs K L thereon. At the other side of the bridge- 70 way I may have a similar gate closing toward the first and operated by a similar rock-shaft, arm, and lugs, except that the arm I and lugs K L must be located on the upper side of the rock-shaft instead of the lower side. 75

On the lower side of the bridge I attach a rod or trip a foot or so in length, as shown in Fig. 2. When the gate begins to swing, the trip R strikes the lug L, rocking the rock-shaft G, throwing the post C forward, and 80 allowing the gate to fall into position with support F resting on the ground, closing the approach to the bridge. As the bridge swings, it will be seen that the rod R moves the lug L around until it is in a horizontal instead of a 85 perpendicular position, and brings the lug K into a vertical position. When the bridge is closed again, the trip R strikes the lug K, rotating the shaft in the opposite direction, causing the post C to assume a vertical position again. 90

Where the bridge revolves clear around instead of half-way and back, stationary rods or trips R would not answer for the closing and opening of the gate. I therefore pivot the 95 trip R to the bottom of the floor of the bridge or to piece S at point T, and fasten it to the endless chain U, which passes around the pulleys V, and is also attached to hand-wheel or a lever, W, which is so placed that the mo- 100

tion that rings a gong or bell to warn parties that the bridge is going to open may operate the chains or rods U, and with them the trip R, which strikes against the lug L and closes the gate before the bridge moves. As the bridge moves around, the motion of lever or wheel W is reversed, throwing the trip R far enough around on its pivot to clear the lug K as they swing past in closing, when the lever can be reversed and the trip R caused to strike lug K on its inner side and open the gate again.

The arm G is concealed, in practice, beneath a floor or covering having a hole large enough for post C to play through, but only cut away far enough on the inside to fall to about an angle of forty five degrees, when the side of the cut-away part acts as a stop.

My gate can also be used as a farm-gate or at railroad-crossings as well as at bridges.

What I claim is—

1. In gates to close the approach to bridges, the gate A, post C, rock-shaft G, and lugs K L, as and for the purpose set forth.

2. The gate A, pivoted on the vibrating post C and having the shifting gravitating weight D attached to its rear end, as and for the purpose set forth. 25

3. The combination, with the gates A A', rock-shafts G G', posts C, and lugs K L M N, 30 of the trips R R' on the bridge, as and for the purpose set forth.

4. The combination, with gates A A', posts C C', rock-shaft G', having lugs below it, and rock-shaft G, having lugs on its upper side, of 35 the trips R R' on the bridge, one mounted above the other, as and for the purpose set forth.

5. The combination, with the lugs on the rock-shaft of gate A, of the trips on the bridge 40 and lever W, by means of which and the connecting mechanism the trips are made to operate the gate, as and for the purpose set forth.

CHARLES K. CORDREY.
